UNITED STATES PATENT OFFICE.

WILLIAM GAMBLE AND MALCOLM OWEN, OF LONDON, ENGLAND; SAID GAMBLE AS-
SIGNOR TO A. W. PENROSE AND COMPANY LIMITED, OF LONDON, ENGLAND.

APPARATUS FOR APPLYING SHEETS TO PRINTING CYLINDERS.

Application filed March 19, 1923. Serial No. 626,091.

To all whom it may concern:

Be it known that we, WILLIAM GAMBLE and MALCOLM OWEN, both subjects of the King of Great Britain, residing at London, 5 England, have invented certain new and useful Improvements in Apparatus for Applying Sheets to Printing Cylinders, of which the following is a specification.

This invention relates to apparatus for 10 applying sheets for use as printing surfaces to printing cylinders.

The main object is to obtain a firm and even surface on the sheet after wrapping has been effected, so that the best printing 15 results are obtainable and especially so that sheets may be removed and replaced on cylinders and can be kept for further work if desired.

Another object is to construct in as simple a form as possible an apparatus adapted to put the sheet under tension over its 20 whole area during the whole wrapping operation.

In the accompanying drawings is illustrated a preferred construction embodying 25 the present invention.

Fig. 1 is a side elevation of the tension apparatus; and Fig. 2 is a plan of the tension apparatus.

Referring to the drawings, the numerals 30 1 and 2 indicate longitudinal and transverse members of a framework, at one end of which is disposed on the longitudinal, bearings 3 for the reception of a spindle 4 adapted to carry a printing cylinder, indicated by the numeral 5. The bearings are 35 open at the top so that the spindle may be immediately removed, if required, by lifting it from the bearings.

On the spindle at one end, outside a bearing 3, is fixed a worm wheel 6, and fitted 40 on the adjacent longitudinal is a worm 7, adapted to be operated by any means, such, for instance, as the handle 8.

At the other end of the framework, bearings 9 are arranged on the longitudinal in 45 the same manner as the bearings 3, the bearings 9 also being preferably open for the direct reception of a spindle 10, on which 50 is mounted a sprocket wheel 11 arranged centrally of the frame. At one end of the spindle 10 is mounted a brake drum 12, about which is fitted a friction device 13,

which may be adjustable about the drum by means of the device 14, the segments of 55 the braking device being pivotally connected, as indicated at 15, to an adjacent portion of a longitudinal member 1. The rotation of the member 14 causes the segments of the device 13 to move about their pivot 60 in order to vary the frictional engagement with the drum 12. Fixed near the periphery of the sprocket wheel 11 is a chain 16, which is adapted to wrap round the sprocket 65 wheel, and which carries at its free end a clamping element 17 for attachment of a sheet 18 intended to be wound around the printing cylinder 5. In order to maintain the clamping bar parallel with the axis 10, the clamping bar is connected to the chain 70 16 by means of a block 19 carrying a toothed wheel 20, over which passes a second chain or other flexible member 21, connected to both ends of the clamping bar.

In use, one end of the sheet 18 is fitted 75 to the usual gap 22 formed in the printing cylinder, and the other end is attached to the clamping bar 17. The sprocket wheel is then rotated to coil the chain around it 80 until the sheet 18 is pulled out and strained under tension. The braking device is then applied until it prevents any reverse rotation of the spindle 10 which would slacken the tension in the sheet. Due to the position of the bearings one to another on the 85 platform, the sheet, when so strained, is disposed tangentially to the periphery of the cylinder 5; then to wrap the sheet 18 around the cylinder 5, the worm 7 is rotated, and by gearing with the worm wheel 6, causes the cylinder 5, mounted on the spindle 4, to 90 be rotated away from the tensioning device and to wrap the sheet 18 around it, while the tension applied to the sheet is maintained.

It may here be pointed out that the worm 95 7 prevents a reverse rotation of the cylinder 5 which the tension of the sheet tends to effect. The sheet having been wrapped entirely round the cylinder until its end attached to the clamping bar 17 overlaps the gap 22 in the cylinder, that end of the sheet is then fixed within the gap and the clamping bar released from the sheet, when any extra material may be removed. A 100 convenient method of fixing the end of the 105

sheet (held by the clamping bar) within the gap is described in our concurrent application Serial No. 587,014.

We claim:

5. 1. Apparatus for applying sheets to a printing cylinder comprising the combination with a support of bearings on said support, a spindle adapted to carry a printing cylinder carried by said bearings, gearing 10 for rotating said spindle, a tensioning device fixed on said support and spaced from said bearings, fastening means for attaching said tensioning device to a sheet to be wrapped on a cylinder, and means for preventing reverse rotation of said spindle under effort from said tensioning device.
10. 2. Apparatus for applying sheets to a printing cylinder, comprising the combination with a support, of bearings on said support, a spindle adapted to carry a printing cylinder carried by said bearings, gearing 15 for rotating said spindle, a tensioning device including a rotatable member mounted in bearings carried by said support at a fixed distance from the first mentioned bearings, a brake drum carried by said rotatable member, adjustable friction means operating with said brake drum, a sprocket wheel carried for rotation with said rotatable member, a chain fixed at one end on the periphery of said sprocket 20 wheel, and a clamp connected to the other end of said chain.
15. 3. Apparatus for applying sheets to a printing cylinder, comprising the combination with a support, of bearings on said support, a spindle adapted to carry a printing cylinder carried by said bearings, a worm 25 wheel on said spindle, a worm engaging said worm wheel, a handle for operating said worm, a tensioning device including a rotatable member mounted in bearings carried by said support at a fixed distance from the first mentioned bearings, a brake drum carried by said rotatable member, adjustable friction means operating with said brake drum, a sprocket wheel carried for rotation with said rotatable member, a chain fixed at one end on the periphery of said sprocket 30 wheel, and a clamp connected to the other end of said chain.
20. 4. Apparatus for applying sheets to a printing cylinder, comprising the combination with a support, of bearings on said support, a spindle adapted to carry a printing cylinder carried by said bearings, a worm 35 wheel on said spindle, a worm engaging said worm wheel, a handle for operating said worm, a tensioning device including a rotatable member mounted in bearings carried by said support at a fixed distance from the first mentioned bearings, a brake drum carried by said rotatable member, adjustable friction means operating with said brake drum, a sprocket wheel carried for rotation with said rotatable member, a chain fixed at one end on the periphery of said sprocket 40 wheel, and a clamp connected to the other end of said chain.
25. 5. Apparatus for applying sheets to a printing cylinder, comprising the combination with a support, of bearings on said support, a spindle adapted to carry a printing cylinder carried by said bearings, a worm 45 wheel on said spindle, a worm engaging said worm wheel, a handle for operating said worm, a tensioning device including a rotatable member mounted in bearings carried by said support at a fixed distance from the first mentioned bearings, a brake drum carried by said rotatable member, adjustable friction means operating with said brake drum, a sprocket wheel carried for rotation with said rotatable member, a chain fixed at one end on the periphery of said sprocket 50 wheel, and a clamp connected to the other end of said chain.

of said sprocket wheel, a clamp connected to the other end of said chain, and means for preventing reverse rotation of said spindle under effort from said tensioning device.

4. Apparatus for applying sheets to a printing cylinder, comprising the combination with a support, of bearings on said support, a spindle adapted to carry a printing cylinder carried by said bearings, a worm 55 wheel on said spindle, a worm engaging said worm wheel, a handle for operating said worm, a tensioning device including a rotatable member mounted in bearings carried by said support at a fixed distance from the first mentioned bearings, a brake drum carried by said rotatable member, adjustable friction means operating with said brake drum, a sprocket wheel carried for rotation with said rotatable member, a chain fixed at one end on the periphery of said sprocket 60 wheel, and a clamp connected to the other end of said chain.

5. Apparatus for applying sheets to a printing cylinder, comprising the combination with a support, of bearings on said support, a spindle adapted to carry a printing cylinder carried by said bearings, a worm 65 wheel on said spindle, a worm engaging said worm wheel, a handle for operating said worm, a tensioning device including a rotatable member mounted in bearings carried by said support at a fixed distance from the first mentioned bearings, a brake drum carried by said rotatable member, adjustable friction means operating with said brake drum, a sprocket wheel carried for rotation with said rotatable member, a chain fixed at one end on the periphery of said sprocket 70 wheel, and a clamp connected to the other end of said chain.

In testimony whereof we affix our signatures.

WILLIAM GAMBLE.
MALCOLM OWEN.
